Primary Examiner — Mark A Goodwin(74) *Attorney, Agent, or Firm* — Will Hunziker(57) **CLAIM**

The ornamental design for an agricultural device, as shown and described.

DESCRIPTION

FIG. 1 is a bottom perspective view of an agricultural device showing our new design.

FIG. 2 is a front view thereof.

FIG. 3 is a back view thereof.

FIG. 4 is a bottom view thereof.

FIG. 5 is a top view thereof.

FIG. 6 is a left side view thereof; and,

FIG. 7 is a right side view thereof.

1 Claim, 4 Drawing Sheets(56)
